UNITED STATES PATENT OFFICE.

WILLIAM R. GROGER, OF EL SEGUNDO, CALIFORNIA.

CROSS-LINE-PUZZLE GAME.

Application filed January 18, 1927. Serial No. 161,789.

My invention is a cross line puzzle game in which a board is laid out with squares or similar markings on opposite sides, and a series of lines lead in various directions connecting the squares on opposite sides of the board. The board may be used to work out puzzles or to play contests with opposing parties, or to play a game somewhat similar to checkers.

10 An object of my invention is the construction of a game board and the playing of the game, or games and puzzles, in which the board is laid out with squares or other markings on opposite sides. These squares 15 are connected by a series of lines, the lines crossing each other and there being preferably two or more lines from any given square to two or more other squares.

In addition, the board is provided with 20 numbers in the squares and on the two sides without the squares for the placing of playing pieces thereon, these pieces preferably being numbered. In one type of game or 25 puzzle a certain number of playing pieces, less than the total number of squares, may be placed on the board one after the other and then moved from one square to the square connected thereto by the cross lines, and left; the object being to fill all the 30 squares but one with the playing pieces without becoming blocked.

Another game is for opposing sides to take an equal number of playing pieces and endeavor to place them on the board in such 35 manner as to block the path of the opponent.

Further games and puzzles may be played by placing the playing pieces around the board on the numbers and jumping one piece 40 over the others to always total a certain number of pieces jumped, and continue this operation until they are stacked two deep.

Another type of game is in the cross lines to have stopping places marked at the intersection of the lines so that the playing pieces may stop on these and change their direction of move along the intersecting line. With this type of board, a game somewhat similar to checkers may be played by 50 opposing players.

My invention in its various aspects will be more readily understood from the following description and drawings, in which:

Figure 1 is a plan of a board showing one form to play puzzles or games thereon. 55

Figure 2 is a side elevation of the board illustrating a playing piece thereon.

Figure 3 is a perspective view of one of the playing pieces.

Figure 4 is a plan of a different type of 60 board for playing different games, preferably games of the nature of checkers.

Referring to Figs. 1 and 2, the board is designated by the numeral 1 and has a series of squares 2 thereon, these squares having 65 numbers designated by 3, being 1 to 6 and 11 to 16. The squares are joined by lines 4 which preferably lead from the corners of certain squares to the corners of certain other squares. Some of these lines may be 70 drawn to intersect as indicated by the numeral 5, that is the lines from the corner of one square crossing over each other. In addition to the lines and the squares with the numbers, there are a series of numbers indicated by the numeral 6 on the ends of 75 the board. In the present instance these are 7 to 10 and 17 to 20.

The playing pieces 7 are preferably cylindrical blocks and these are preferably numbered on the side, as indicated at 8, and have 80 similar numbers 9 on the top. On a board having 20 numbers, there would be 20 playing pieces.

In the game board of Fig. 4 the squares 85 are substantially the same as in Fig. 1 and numbers on the ends of the boards are substantially the same, however, it is desirable to rearrange the cross lines so that there will not be a number of lines crossing at the same 90 point and to avoid this certain of the lines as indicated by numeral 10, may have a curve therein. There are also additional lines 11 which do not meet the squares but terminate at some of the cross or diagonal 95 lines. A series of stopping places 12 are indicated at the intersection of the various diagonal lines and the curved line or lines 10 and the short lines 11. There are other stopping places 12' which are not on intersections. These are preferably enlarged dots or the like and may be in various colors. It

is to be understood that in these boards, as illustrated, I have only shown two lines extending from each square so that the board 100 or diagram will not be too complicated. 105

One of the puzzles which may be worked out, say on the board of Fig. 1, is to take a series of pieces, 11 in number, there being 12 squares on the board, and to place these one after the other on certain squares and then move them to other squares in order to get the 11 pieces on the board without being blocked, as a playing piece cannot be put on a square which is already occupied by another playing piece. The pieces are to be moved only on the angular or diagonal lines from one square to another. Thus a person may, for the first move, jump from 2 to 16, second move 15 to 2, third 3 to 15, fourth 13 to 3, fifth 6 to 13, sixth 11 to 4, seventh 5 to 11, eighth 12 to 6, ninth 14 to 5, tenth 1 to 12, and eleventh 1 to 14. It will be found with a less number of vacant spaces on the board that it is more difficult to work out this puzzle without becoming blocked.

Another game of a contesting nature which may be played is for opposing players to take, say, an equal number of playing pieces, equal to or less than the number of squares, and the players playing from opposite sides of the board will put their pieces one after the other on certain squares and move them to squares on the opposite sides. The player who first blocks the other from moving, winning the game.

Another type of puzzle is to position the playing pieces, either a less or a total number of numbers indicated on the board, the total being 20, in a consecutive order around the board in accordance with their numbers and then endeavor to jump a certain number of playing pieces and land on a piece allowing building up of the entire number in a double set. This puzzle or game can be only played with an even number of pieces. For instance, presume that 14 pieces were used, and are placed on the table in the squares 1 to 6 and 11 to 14, and on the numbers 7 to 10, an object of the game might be to jump a playing piece over eight other pieces and land on the ninth until these were built up in seven sets of two pieces each. A first move may be jumping from 11 to 6 passing over 12, 13, 14, 1, 2, 3, 4 and 5, landing on 6; move 2, 1 to 9 passing over 2, 3, 4, 5, 6, 11, 7 and 8, landing on 9; move 3, 5 to 13 passing over 6, 11, 7, 8, 9, 1, 10, and 12, landing on 13. In this game where two pieces are stacked one on the other they count as two pieces. Fourth move jump 2 to 7 passing over 14, 5, 13, 12, 10, 1, 9 and 8, landing on 7; 5th move jump 4 to 12 passing over 6, 11, 2, 7, 8, 1, 9, 10, landing on 12; 6th move jump 3 to 8 passing over 14, 13, 5, 4, 12, 10, 1 and 9, landing on 8; 7th move jump 10 to 14 passing over 1, 9, 3, 8, 2, 7, 6 and 11, landing on 14. This will be found to make seven stacks two deep.

This puzzle has great variety and a various number of jumps may be made but the

piece being moved must land on a single piece and cannot stop on a built up stack of two and if the player cannot jump without this latter, he is blocked from winning the puzzle or the game.

In using the board of Fig. 4, a game somewhat similar to checkers may be played. In this case the opposing players place their playing pieces or men on the numbered squares and also reserve pieces, if desired, in the spaces between the squares. The rules of the game may call for a player to move in a general direction which will take him from his side of the board to the opposite side of the board. The rows of squares are called the king rows. If a player has an opportunity to jump his opponent's playing piece, he must do so. In this game the player can only move from a square to one of the stopping points or dots 12 at the intersection of the lines or where marked on the lines without intersections. When he moves a piece out of his back or king rows, he may move one of the reserve pieces into the square vacated, this being an extra move. If an opponent's playing piece should be on a stopping place on the same line as that of the person playing, they may jump backward to capture such opponent's playing piece, and also jump forward. Therefore, if one opponent gets any of his pieces behind the forward row of the opposing player, he runs a risk of losing such piece.

When a player gets any piece to the opposite side of the board it should be crowned and may move in any direction, the same way as a king in checkers. The player who first eliminates the playing pieces of his opponent, wins the game in the same manner as in checkers.

In this game it will be noted that the lines 11 do not lead from one square to the other but allow the player to shift laterally from one end of the board towards the other without crossing to the squares. Also that there 110 may be one or more curved lines 10 which may be so shaped as to intersect different ones of the straight diagonal lines.

It will be obvious that the board of Fig. 4 may be used to play a number of games 115 which may be played on Fig. 1 and also similar puzzles may be worked out thereon, and also that a game somewhat simulating checkers may be played in various manners on the board of Fig. 4.

Various changes may be made in the principles of my invention without departing from the spirit thereof, as set forth in the description, drawings and claims.

I claim:

1. In a cross line puzzle a rectangular board having a series of squares on opposite sides, said squares being spaced apart and numbered, a series of numbers on the remaining two sides of the board, the numbers 130

on the squares and the numbers on the sides of the board following consecutively around the periphery of the board.

2. In a cross line puzzle a rectangular board having a series of spaced apart squares on opposite sides of the board, said squares being numbered and there being numbers on the two remaining sides of the board, the numbers being in consecutive order around the periphery of the board, and a plurality of continuous cross lines from each of the squares to one or more other squares on opposite sides of the board.

3. A cross line puzzle having a rectangular board with squares on opposite sides, with numbers on each square, a plurality of continuous crossing lines from each of the squares to a square or squares on the opposite side of the board, and playing pieces having numerals thereon.

4. A cross line puzzle, as claimed in claim 3, some of the crossing lines intersecting

and having marks for stopping places at the intersections.

5. In a cross line puzzle, a board having a series of squares spaced apart on opposite sides of the board, a plurality of continuous crossing lines from each of the squares to a square or squares on the opposite side of the board, some of said lines intersecting, curved continuous crossing lines from some of the squares to some of the other squares, also intersecting some of the straight crossing lines, and short lines between some of the crossing lines, there being marks for stopping places at the intersections of the various lines, and in addition numbers on the squares and numbers on the sides of the board other than those occupied by the squares.

In testimony whereof I have signed my name to this specification.

WILLIAM R. GROGER.
